UNITED STATES PATENT OFFICE.

MAGDALENA DE LOS S. ENRIQUEZ, OF NEW YORK, N. Y.

LADY'S GARTER.

1,338,858.

Specification of Letters Patent.

Patented May 4, 1920.

Application filed June 20, 1919. Serial No. 305,659.

To all whom it may concern:

Be it known that I, MAGDALENA DE LOS S. ENRIQUEZ, a citizen of Mexico, and a resident of New York city, in the county and 5 State of New York, have invented certain new and useful Improvements in Ladies' Garters, of which the following is a full, clear, and exact description.

Among the principal objects which the 10 present invention has in view are: To avoid the damage to ladies' stockings incident to supporting the same in service; to increase the comfort of stockings in service; to prevent sag or wrinkling of the stocking below 15 the knee of the wearer; and to provide an ornamental article of the character mentioned.

Drawings.

Figure 1 is a view showing the outer portion of the human leg, the upper end of a stocking installed in service thereon, and a garter for holding the stocking in place, said garter being constructed and arranged in accordance with the present invention.

Fig. 2 is a detail view showing the inside of the garter in its extended or opened position.

Description.

The present invention is particularly designed to overcome the objection to stocking supporters where straps are attached to the corsets and to the stockings for holding the stockings in service position, and where the 35 full strain of the pull of the strap is imparted to the top of the stocking, to the effect that often the stocking is pulled apart or torn by the fastener securing the same to the strap.

Furthermore, in service, strap supported stockings are apt to wrinkle below the knee, incident to the fact that when assumed in the sitting position, the wearer of the stocking stretches the upper portion of the stocking 45 above the knee without the strain thereon being distributed to the portion of the stocking below the knee. When the person wearing the stocking assumes an upright position, the stretch thus imparted to the 50 stocking results in a fullness in the stocking below the knee, with the consequent wrinkling thereof.

It is desired to hold the stocking snugly 55 on the leg below the knee. With this object in view, the present invention provides the lower partly elastic strap. The partly elas-

tic strap is constructed of elastic sections 7 and 8, and sections of the non-elastic supports 9 and 10. The combined sections 7 and 8 and supports 9 and 10 provide that the sections 7 and 8 may be stretched when the garter is placed in service on the leg. When in service, the ends of the garter are united, using for this purpose, a buckle having male and female members 11 and 12. 60 The members 11 and 12 are of usual construction, the latter consisting of a ring having a relatively sunken recessed portion, through which, and into which, the portion 11 extends and rests. 65

The supports 9 and 10 are shaped and elongated to extend from below to above the knee of the person wearing the garter. The supports 9 and 10 are provided, adjacent their extremities, with loops 13, through 70 which is run elastic webbing 14. The webbing 14 has fasteners 11 and 12, as are provided on the section 8 and the supporter 10, where the same extend below the knee. 75

The garter formed by the webbing 14 is 80 arranged to fit the upper portion of the leg of the wearer of the stocking, approximately where the top of the stocking usually rests. The purpose of the webbing 14 is to retain 85 the stocking and to prevent the same from falling.

When placing the garter in service, the sections 7, 8, and the portions of the supporters 9 and 10 in line therewith, are disposed below the knee-cap and above the calf 90 of the leg. The portion of the garter formed by the web 14 is fastened about the upper portion of the leg above the knee-cap. When the two garter portions are secured, it is obvious that when the leg is bent at the 95 knee, the front portion of the stocking is slightly stretched, the garter formed by the webbing 14 permitting this action. The slack thus imparted to the stocking in the region between the two garter sections is not 100 permitted to encroach upon the area of the stocking below the lower garter section, hence, the visible part of the stocking has always a neat and snug appearance, while freedom is imparted to the movement of the 105 leg.

Adjacent the extremities of the supporters 9 and 10, said supporters are provided with eyelets 15 and 16. These eyelets are preferably metal eyelets of the general 110 type worn in shoes, for lacing. The openings in the eyelets is sufficiently large to re-

ceive the button-like head 17 provided on one of the members of the usual fasteners secured to elastic stocking supporters 18. An eyelet plate 19 is usually provided on the 5 stocking supporter which has an eyelet 20, the enlarged portion of which, permits the passage of the head 17, while the contracted portion of which, engages the shank of the head 17, and prevents the passage of the said 10 head therethrough.

It will be understood that unlike the present method of securing the stocking, where sections of the fabric thereof, are forced through the eyelet 20 by the head 17, in the 15 present case, the head 17 is not directly engaged with the fabric of the stocking.

The eyelets 15 and 16 are disposed in spaced relation as shown in the drawings to accommodate supporters such as indicated 20 by the numeral 18 of various lengths, also to accommodate the variation to be found in the length of the leg of the wearers of the garters. It will be understood that the supporters 18 are attached to the skirt of the 25 corset or to the belt sometimes substituted therewith.

It will be readily seen that any undue strains which may be imparted by the supporters 18 will be taken up by the supporters 9 and 10, and the danger of tearing 30 the stocking will be thereby obviated.

Claims.

1. A garter comprising a plurality of non-

elastic supporting members each having a 35 series of button holes disposed lengthwise thereof in spaced relation for engagement by the clasp of the usual stocking supporter; a plurality of elastic connectors uniting in service said supporters to form in conjunction therewith an open ended partially elastic band for encircling the leg below the knee; an open ended continuous elastic band for encircling the leg above the knee; and a 40 plurality of guide loops formed on said supports adjacent the upper end thereof for loosely holding said continuous band in 45 service.

2. A garter comprising an open ended band for encircling the leg below the knee, 50 said band embodying a plurality of elastic sections disposed in spaced relation to one another, the ends of said sections being permanently attached to the sides of non-elastic supports, a plurality of said supports, each 55 having a vertical extension above said band to extend above the knee of the wearer, said supports having a series of eyelets vertically disposed in spaced relation for being adjustably connected to the attaching device 60 of a strap supporter; a plurality of guide loops mounted on said supports adjacent the upper ends thereof; a continuous elastic open ended band for extension through said 65 loops for encircling the leg of the wearer above the knee; and means for fastening the ends of said bands in service.
